UNITED STATES PATENT OFFICE.

THOMAS S. PATTERSON, OF ROSEMONT, PENNSYLVANIA, ASSIGNOR TO THE OIL AND WASTE SAVING MACHINE COMPANY, OF PHILADELPHIA, PENNSYLVANIA, A CORPORATION OF PENNSYLVANIA.

CENTRIFUGAL SEPARATOR.

No. 926,596.

Specification of Letters Patent.

Patented June 29, 1909.

Application filed February 1, 1907. Serial No. 355,305.

To all whom it may concern:

Be it known that I, THOMAS S. PATTERSON, a subject of the King of Great Britain and Ireland, residing at Rosemont, Pennsylvania, have invented certain Improvements in Centrifugal Separators, of which the following is a specification.

The object of my present invention is to provide a removable screen for a centrifugal separator for removing oil or grease from waste material so that after the oil is separated, the material can be bodily removed with the screen from the basket of the centrifugal machine.

Some classes of material, such as ordinary cotton or woolen waste having long fibers, can be readily removed from the basket of the separator in bulk, but material having short fibers, which will densely pack against the walls of the basket, is very difficult to remove and I have found by making a separate screen which can be bodily removed with the material from the basket that the screen can be opened and readily freed from the material without waste of time and without injury to the basket of the separator.

In the accompanying drawings:—Figure 1, is a vertical sectional view of a centrifugal separator illustrating my invention; Fig. 2, is a side view of the removable screen detached from the machine; Fig. 3, is a perspective view of the cover of the screen; Fig. 4, is a perspective view of the side walls of the screen showing the ends detached; Fig. 5 is a detached view showing part of the cover of the screen; Fig. 6, is a detail view of portions of the screen; Fig. 7, is a view of a modification showing a hinged screen; and Fig. 8, is a detail of Fig. 1, showing a portion of the basket and screen.

A is the base of the centrifugal separator, A' is the outer shell forming a chamber in which is mounted the basket B carried by a spindle B' mounted in a bearing a. The basket B has a central hub b and a perforated shell b', and depending from the base of this basket are blades c against which impinges the steam from a nozzle c' connected to the pipe C. There is thus formed a turbine engine for driving the basket and the exhaust steam passes around and through the basket, acting to liquefy the oil so that it can be readily freed by centrifugal force from the waste material.

A² is a cap plate closing the chamber and

G is a pipe communicating with the bottom thereof and having a trap g. This pipe is for the purpose of drawing off the oil or grease as it accumulates. I have shown in the present instance a lubricant reservoir M connected by pipes m, m', with the bearing and in the bottom of the bearing a is a step bearing a' upon which the spindle B' rests. This form of bearing and the construction of the lubricator is fully set forth and claimed in an application for patent filed of even date here-with, bearing Serial Number 355,304.

E is the removable screen, being of such dimensions as to snugly fit within the basket B, as shown in Fig. 1, its base flange e resting upon the bottom thereof. This screen consists, in the present instance, of a lower flange e and an upper flange e' connected together by vertical bars e² forming a frame for the wire gauze E', which may be of any mesh desired. This frame is in fact a flexible perforated band, the ends x, x' of which may be united in any suitable manner; in the present instance I have shown buttons f, f on the part x adapted to slots f' on the part x', as clearly illustrated in Figs. 4 and 6.

I is a cover plate for the screen frame E and this cover plate is preferably made of cast metal having a flange i which extends over the upper flange e' of the screen E. In the present instance, in the flange i is a right angled recess i² which is shaped for the reception of buttons h on the screen frame E, forming in fact a bayonet joint. The cover plate I is open at the center i' so that the steam can freely flow through the screen frame.

k, k are eyes secured to the cover plate so that the plate with the screen frame can be readily removed by any suitable hoisting apparatus.

In operation the two ends of the screen frame are secured together and the cover plate is attached as shown in Fig. 2, the screen frame being then placed within the basket B of the centrifugal machine. The machine is loaded with saturated or coated waste and the cover A² placed in position. Steam is then introduced into the pipe C and the steam jet impinging upon the blades c of the basket causes the basket to rotate rapidly. The exhaust steam passing through the basket and through the material therein will liquefy the oil so that it can be more readily removed from the material.

The oil or grease will pass through the screen E' of the screen frame and through the perforations in the walls of the basket into the outer chamber, from which it is withdrawn 5 through the pipe G. When all the oil or grease is extracted from the material, the cover A² is removed and the screen frame with the material therein is bodily removed from the basket. The cover plate I is then 10 detached from the screen frame E and the two parts of the screen are unlocked. The screen is separated so as to increase its diameter, thereby causing the gauze to separate from the material when it can be readily removed, leaving said material in bulk. The 15 screen can then be assembled, replaced in the basket and the operation repeated.

While I have shown in Fig. 4, the screen frame made of a flexible band of metal and a 20 flexible screen, the parts may be hinged, as shown in Fig. 7, without departing from the invention.

I claim—

1. The combination in a centrifugal separator, of a rotating basket, a screen frame in 2 the form of a band mounted in the basket, with means for detachably connecting the adjacent edges of said screen frame.

2. The combination in a centrifugal separator, of a basket open at the top, a cylindrical 3 frame removably mounted within the basket, said frame having screened sides and an open bottom, and a cover detachably secured to the screen frame, the said sides of the frame being capable of being expanded to discharge 3 the contents thereof when removed from the basket and having means whereby they are detachably connected to each other.

In testimony whereof, I have signed my 4 name to this specification, in the presence of 4 two subscribing witnesses.

THOMAS S. PATTERSON.
